FITMENT AND CLOSURE FOR PACKAGING CONTAINERS

Edward H. Lawton, Toledo, Ohio, assignor to Owens-Illinois Glass Company, Toledo, Ohio, a corporation of Ohio

Filed Nov. 13, 1962, Ser. No. 72,473

Term of patent 14 years

(Cl. D58—8)

FIG. 1

FIG. 4

FIGURE 1 is a perspective view of a fitment and closure for packaging containers, showing my new design;

The portions shown in broken lines are for illustrative purposes only.

I claim:

The ornamental design for a fitment and closure for packaging containers, substantially as shown and described.
